UNITED STATES PATENT OFFICE.

EUGENE SILAS SUTTON, OF LEAVENWORTH, WASHINGTON.

FRUIT-BOX PRESS.

1,237,971.

Specification of Letters Patent. Patented Aug. 21, 1917.

Application filed September 14, 1916. Serial No. 120,080.

To all whom it may concern:

Be it known that I, EUGENE S. SUTTON, a citizen of the United States, residing at Leavenworth, in the county of Chelan and 5 State of Washington, have invented certain new and useful Improvements in Fruit-Box Presses; and I do declare the following to be a full, clear, and exact description of the invention, such as will enable others skilled 10 in the art to which it appertains to make and use the same.

This invention relates to improvements in machines for pressing and packing fruit in crates, boxes and similar containers preparatory to shipment.

It is well known that when boxes of fruit of various kinds are packed, the top layers generally extends an inch or so above the top of the box so that it is necessary in some 20 manner to force the ends of the slats which form the cover down so that they may be readily nailed to the ends of the box. My invention is designed to press and hold down the slats forming the cover of the fruit box 25 until they are nailed in position.

The principal object of the invention is to provide a very simply constructed machine which can be inexpensively manufactured and yet which will be very efficient in 30 operation.

An additional object is to provide a very simply constructed frame for use in connection with the other parts of the machine for more quickly and readily forcing the 35 slats into position.

With these and other objects in view, the invention resides in the numerous features of construction and arrangement of parts which will hereinafter be more fully described and claimed.

In the accompanying drawings:

Figure 1 is a perspective view of a box press constructed in accordance with my invention, showing the parts of the same in 45 operative position;

Fig. 2 is a similar view with the parts inoperative;

Fig. 3 is a vertical section through the box press;

Fig. 4 is a still another vertical section taken on the plane at right angles to the 50 plane of Fig. 3.

In the several figures of the drawings, I have shown my invention constructed in the 55 preferred manner, it consisting broadly of a suitable supporting table 1 having a top

or platform 2 supported by legs or the like 3, upon which a crate or box C containing fruit is positioned, while the cover is forced into place by an improved press which will 60 later be more particularly described. The table is suitably braced and constructed any desired size depending upon the size of the crates which are to be disposed thereon.

At the rear corners of the table, uprights 65 4 are disposed and secured rigidly in any desired manner, and between these uprights is a support 5, its lower end being secured to the top of the table, while its upper end is braced by the cross bar 6 which connects the 70 upper ends of the uprights 4. The support 5 is designed to carry a cam lever 7 which is pivoted between outwardly extending spaced apart arms 8, said arms projecting from the support 5 adjacent its connection with the 75 brace bar 6. The support 5 is substantially in the middle of the platform 2 and at its rear edge, and therefore the lever 7 is extended over the central portion of the latter.

On the top or platform 2 at its side edges 80 is secured the carriage by which a crate may be readily moved into position beneath the operating lever 7. This carriage comprises a pair of roller carrying rails 9, one 85 of which is disposed at each side edge of the platform 2 and has a plurality of rollers 10 upon which the crate C rests. In order to guide the crate during its movement from the front of the platform to the rear thereof, suitable guide strips 11 are secured to the rails 9 as shown. These strips are spaced apart a distance to receive a crate of ordinary length. A stop strip 12 also is disposed at the rear edge of the platform 2 90 and co-operates with the support 5 to limit the movement of the crate.

After the filled crate C has been moved into position beneath the operating lever 7 as shown in Fig. 1, the two or more slats 13 100 which comprise the top thereof are disposed on the box or crate in the usual manner. A clamping or pressing frame 14 of improved construction is then placed on the slats beneath the lever 7, said lever being in upright position. After the parts are thus assembled, the handle of the lever is moved downwardly and the cam 15 with which it is provided engages the frame 14 and presses the ends of the slats 13 into engagement with the ends of the crate. This cam lever is so pivoted between the arms 8 that 110

it will stay in its lowered or clamping position without holding, thus allowing the cleats 16 to be nailed across the ends of the slats 13.

5 The frame 14 is constructed of a pair or more longitudinal strips 17 depending upon the width of the crate upon which it is to be used, and a pair of transverse end pieces or strips 18, one of which connects each end 10 of said strips 17. A bearing member in the form of a rather wide transverse strip 19 is secured across the central portion of the strips 17 and receives the pressure from the operating lever 7, the cam 15 of the latter contacting therewith. Each of the strips 17 has its lower face recessed in its intermediate portions, thus forming enlarged depending parts 20 at each end. The strips 18 are secured to these enlarged parts 20, 20 thus when the frame is engaged with the slots 13, the bottom edges of the strips 18 will be the only parts which come into contact therewith, the central portion of the frame being spaced a considerable distance 25 above the central portions of the strips. This arrangement permits the ends of the slats to be forced downwardly into engagement with the ends of the crate without pressing the fruit in the central part of the 30 container. Any other means might be employed for extending the ends of the frame below the central portion, but that shown is the most simple and therefore preferable.

In addition to the other means, this 35 proved pressing machine is provided with slat or cleat holders on each side of the table 1. These holders consist of a pair of extensible arms 21 which project beyond the edges of the platform 2 as shown at Fig. 1 40 and conveniently support a number of slats 13 or cleats 16 so that they may be quickly applied by the operator. When the machine is not in use, or when it is not desired to support slats or cleats on the holders, the 45 same may be pressed inwardly beneath the platform 2, this being allowed by the seats 22 which are formed in the brace bars 23.

In such a machine as above described, 50 covers may be applied to crates with greater rapidity than with machines now on the market because of the fact of the improved construction of the clamping or pressing frame and the cam lever which operates therewith.

55 The few parts of which the machine is constructed allows the same to be manufactured very inexpensively and readily repaired.

I claim:—

60 1. In a device of the class described, a

table adapted to support a crate, clamping means movable toward and away from the top of said table, and a clamping frame disposed on said crate and comprising a longitudinally extending strip, the end portions 65 of said strip being extended below the plane of the bottom of the intermediate portion and engaged with the cover of said crate.

2. In a device of the class described, a table adapted to support a crate, clamping 70 means movable toward and away from the top of said table, and a clamping frame to be disposed on said crate and comprising a plurality of longitudinally extending strips, said strips engaging said cover, and a trans- 75 verse bearing strip connecting the center portions of the other strips, said strip being engaged by said clamping means.

3. In a device of the class described, a table adapted to support a crate, clamping 80 means movable toward and away from the top of said table, and a clamping frame to be disposed on said crate and comprising a plurality of longitudinally extending strips, the end portions of said strips being extended 85 below the plane of the bottoms of the intermediate portions and engaged with the cover of said crate.

4. In a device of the class described, a table adapted to support a crate, clamping 90 means movable toward and away from the top of said table, and a clamping frame to be disposed on said crate and comprising a plurality of longitudinally extending strips, the end portions of said strips being ex- 95 tended below the plane of the bottoms of the intermediate portions, transverse cleats connecting the bottoms of said extended portions and engaging the cover of said crate, and a transverse bearing strip se- 100 cured to the tops of said longitudinally extending strips, said strip being engaged by said clamping means.

5. In a device of the class described, a table adapted to support a crate, a support 105 disposed at one side of the table, a pair of bearing arms secured to the support, a clamping lever pivoted between said arms, said lever being disposed over the center portions of said table, and a cam on said lever adjacent its pivot, said cam being adapted to engage the cover of said crate. 110

In testimony whereof I have hereunto set my hand in the presence of two subscribing witnesses.

EUGENE SILAS SUTTON.
